SYNCHRONOUS COMMUNICATION SYSTEM

Harry J. Nichols, Dayton, Ohio, assignor to International Business Machines Corporation, New York, N. Y., a corporation of New York

Application May 22, 1933, Serial No. 672,161

64. Claims. (Cl. 178—23)

This invention relates to synchronous communication systems and particularly to single impulse printing telegraph systems.

A general object of the invention is to provide a printing telegraph system in which single signal impulses, distinguished only in respect to time, are utilized to automatically establish synchronism, to provide continuous phase correction to maintain synchronism, and to select the printing characters and printing movements.

A more specific object is to provide a synchronizing and selective system, and suitable apparatus, whereby an electric typewriter, with minor modifications and changes, can be utilized as the printing mechanism of a printing telegraph.

A further object is to provide a printing telegraph system in which the greater part of the apparatus is utilized for both sending and receiving functions with consequent advantages in economy and in simplification.

A further object is to provide a printing telegraph system in which by the simple manipulation by the operator of a single switch, the apparatus is instantly placed in the sending, receiving, or typing condition.

A further object is to provide printing telegraph apparatus utilizing a standard typewriter key board and with both lower case and upper case letters, figures, and characters, with automatic operation of carriage return, shift, spacer, tabulator, and back spacer etc. so that telegraphic communications may be transmitted in the form of the usual commercial or personal letter.

A further object is to provide printing telegraph apparatus of the speed, touch, and key board of a standard typewriter so that typists trained to operate the ordinary typewriter may, without special training, operate the printing telegraph apparatus described in the present invention.

A feature of the present invention is that the typewriter utilized as the printing mechanism of the printing telegraph system herein disclosed, when not being used for the transmission or reception of messages, is equally suitable for typing letters, reports, etc. of the usual nature.

A further object of the present invention is a simple calling signalling arrangement whereby initial calls can be made whether or not the driving motor is running, and while the typewriter is being used for typing, and break-in calls can be made during transmission, the same apparatus being utilized to effect calling signals under the several conditions.

A further object of the invention is to automatically establish and maintain in a positive manner and with exactness, synchronism between transmitting and receiving apparatus at separate points.

A further object is to accomplish such syn-

chronism by means of single impulses transmitted at a definite phase position during each cycle of motion of the transmitting apparatus.

A further object is to accomplish such synchronization by means of signal impulses suitable for transmission over telephone, telegraph or radio communication systems without special adaptation of such systems.

A further object is to maintain close synchronization of the receiving apparatus by correcting, if necessary, and in the degree necessary, the phase position of the controlled element once during each cycle of motion, ensuring that the controlled element moves at all times in close synchronism with the controlling element.

A further object is to provide a governor for driving motors for the synchronized elements which is accurate, sensitive, and quick in response, and which is compensated for temperature effects.

A further object is to provide a governor for the driving motor which permits minor speed adjustments to be made electrically without adjustment of the mechanical settings of the governor and without impairing the range of operation and accuracy of regulation of the governor.

A further object is to provide a motor speed control arrangement whereby means operable from a distance may be utilized to effect a minor adjustment of the motor speed in a predetermined amount without loss of control by the governor.

A further object is to provide a synchronizing arrangement which by simple switching methods is immediately convertible for either controlling or controlled functioning.

A further object is to provide a particular form of electro-magnetic relay and associated circuit and apparatus whereby the relay may be operated by a single current impulse of short duration, and is held in the operated condition as long as similar periodic impulses are applied, and which resumes the unoperated condition when a single periodic impulse is missed.

A further object is to provide a phase correcting mechanism which is simple in construction, accurate in operation, reliable and durable, and which automatically compensates for instrumental and line retardation of signals.

A further object is to provide a smooth acting phase corrector which while in continuous operation, will not tend to change the speed of the controlled element when running in synchronism.

A further object is to provide an electro-magnetic phase corrector which functions to correct the phase position of the controlled element without physical engagement therewith.

A further object is to provide non-repeat means in the sending condition whereby only one signal

is sent to the line for each operation of a type-bar key lever.

A further object is to provide interlock means whereby only one key lever may be depressed at a time.

A further object is to provide key latch and key release means whereby during sending operations, a key lever when depressed is retained in that position until the rotary distributor collects the corresponding signal, whereupon the key lever is released for return to the unoperated position.

A further object is to provide means whereby the key latch is held out of engagement with the key levers after release by collection of the signal, and thereafter as long as the key is held depressed manually, and is permitted to return to the position of engagement with all key levers when the held key is released.

A further object is to provide automatic cut-off means for the electronic relay whereby the current impulses corresponding to the received signal impulses are made of uniform duration irrespective of the duration of the signal impulses.

A further object is to provide duplex transmission means whereby break-in calls may be received when transmitting.

Other objects and features will be in part obvious and in part hereinafter pointed out in connection with the following description taken in connection with the accompanying sheets of drawings forming part of this disclosure.

In the drawings, Figs. 1A and 1B, which are to be considered as parts of the same drawing, show in diagrammatic form the circuits and apparatus which together with the typewriter or printer comprise a complete communication unit. Fig. 1A shows the circuits and apparatus utilized in sending, receiving, and calling. The circuits are shown in the "typing" condition, which is the condition when the selector apparatus is not being used for sending and receiving, and the typewriter is available for typing. Fig. 1B shows the power rectifier providing power for the various relays, magnets, etc. comprising the selecting apparatus, and the distributor driving motor and its control.

Fig. 2 shows in diagrammatic form the circuits and apparatus utilized in sending, and for purposes of explanation is referred to as the sending station or station "A".

General description

A complete installation unit consists of an electric typewriter, a typewriter control assembly, and a distributor unit assembly. The typewriter control assembly is mounted underneath and inside the typewriter frame. The distributor unit assembly is housed in a case, and is located near the typewriter. The two assemblies are connected electrically by a multiple conductor cable.

The principal items of equipment comprising a typewriter control assembly are:

- (a) The key solenoid assembly.
- (b) The key switches.
- (c) The auxiliary switch.
- (d) The key latch.
- (e) The key latch release magnet.
- (f) The key interlock.
- (g) The send-receive switch.

The principal items of equipment comprising a distributor assembly are:

- (a) The rotary distributor.
- (b) The drive motor.
- (c) The rectifier.
- (d) The clutch mechanism.
- (e) The phase-corrector arrangement.
- (f) The electronic relay.
- (g) The cut-off relay.
- (h) The non-repeat relay.
- (i) The duplex transmission arrangement.
- (j) The call circuit.
- (k) The multiple switch relay.

In Fig. 1A, the apparatus comprising the typewriter control assembly is included within the dot-dash rectangle. All other apparatus is included in the distributor unit.

The apparatus shown in Fig. 1A performs the functions of transmitting and receiving printing impulses and synchronizing impulses, both of which classes of impulses are distributed via the rotary distributor. Referring to Figs. 1, 5, 6, the rotary distributor consists of a series of metallic segments 11, and solid metallic ring 12, both mounted on a disc 14 of insulating material, and the rotary brush arm 13, rotatably mounted on and yieldingly driven by the drive shaft 55. The ring and segments, while actually arranged in concentric circles, are shown in linear development in some figures in order to simplify the diagram. The rotary brush arm 13, which makes electrical connection from ring to segments, passes across all the segments once during each revolution in a well understood manner. The drive shaft 55 is conveniently driven at uniform speed by a motor 99, as hereinafter described. The brush arm 13 is shown in the rest position on segment 3.

A clutch release relay 15 is provided to stop and to release the brush arm in accordance with the invention, and for illustrative purposes is shown with its armature 16 in engagement with the brush arm 13. The armature 16 also actuates springs 17 and 18 which function in connection with receiving operations.

The release relay 15 is provided with a low impedance winding 20 and a high impedance winding 21 connected in series. Across the terminals of the winding 21 is connected a storing condenser 22. The outer terminal of the winding 20 is connected to the positive bus 25; the outer terminal of winding 21 is connected to spring 18, to spring 192 of the send-receive switch 190, and to one terminal of the corrector magnet 36. The release relay 15 is of the quick-acting, slow release type, and responds quickly to a short current impulse, but holds for a prolonged period, and if supplied with properly timed impulses continues to hold in the operated position as long as such impulses are regularly received. A relay which so operates is sometimes called a pulse sustained relay, and while other forms of such relays are in use, the particular form here disclosed is novel and constitutes part of the present invention. It is described in further detail hereinafter.

The power for transmission purposes and for the operation of the various relays and magnets is obtained from any suitable direct current source, preferably from the rectifier assembly shown in Fig. 1B. The rectifier assembly consists of the power transformer 210, rectifier tube 211, preferably of full-wave type as shown, the filter condenser 212, and filter choke 213, all connected as shown. The power transformer 210 has a primary 214, connected to the power mains 217; secondary 215 to supply heating current to the cathode of tube 211; center tapped secondary 216 to supply anode current to the tube 211; and secondary 137 with center tap 136 to supply heating current to the cathode of the electronic relay 132.

The output of the rectifier is applied to the terminals of the voltage divider 24a and 24b shown in Fig. 1A. The positive bus 25 is connected to the positive terminal of the voltage divider, and the negative bus 26 to the negative terminal. The zero bus 131 is connected to the zero terminal between sections 24a and 24b of the voltage divider, the section 24b thus furnish-

ing in a well understood manner a negative bias for the grid 133 of the electronic relay 132.

The elements of the electronic relay 132, which is of the grid controlled, gaseous discharge type are the grid 133, the cathode 134 and the anode or plate 135, all contained in an evacuated glass envelope, as is well understood. The center tap 136 of the cathode heating transformer 137 is connected to the zero bus 131.

In series with the plate 135 of electronic relay 132 is the cut-off relay 170, connected as shown, with winding 171 shunted by variable resistor 172, and provided with contacts 173 and 174. As is well known, the grid of a grid controlled gaseous discharge tube is usually unable to stop the discharge when once started, and the plate current is normally cut off by disconnecting the plate supply, or by causing the plate to become negative in respect to the cathode. While either method may be used, it is preferred in the present case to cut off the plate current after a short interval by utilizing the cut-off relay to open the contacts 173-174. The variable resistor 172 permits of very exact timing of the cut-off interval, and the whole arrangement is rugged and reliable. A spark suppressor arrangement may be connected across the contacts 173-174 to reduce sparking to a negligible degree.

The duplex transmission arrangement consists of the sending or output transformer 27 with primary winding 28 and secondary winding 29; and the receiving or input transformer 32 with center tapped primary 33 and secondary 34. The resistor 35, of a suitable value to balance the line impedance, is connected across the secondary 34, 35 and across this resistor 35 appears the potential which overbalances the normal bias on the grid 133, and trips off the electronic relay in a well understood manner. The center tap of the primary 33 is connected to one terminal of the secondary 29, the other terminal being connected to the line terminal 39.

One terminal of the primary 33 is connected to the terminal 30 while the other terminal is connected to line terminal 31 thru the artificial line network A. L. as shown. The functioning of duplex transmission being well understood, the operation is manifest, and does not require discussion beyond that which will be given hereafter in connection with the calling circuits.

The send-receive switch 190 is a three position switch, the three positions being indicated by R. T. S. referring respectively to the receiving, typing, and sending conditions. The switch is of the lever type and has one set of break-make springs, and one set of make springs. These springs are numbered from 191 to 195 inclusive. In the T and S positions, the send-receive switch mechanically holds the universal bar key latch 151 out of engagement with the key levers 156.

The multiple switch relay 160, controlled by the send-receive switch 190, provides the automatic switching operations required to change from sending condition to receiving condition and vice versa. It is provided with a single winding 161, and three sets of break-make contacts numbered from 1 to 9 inclusive. In order to simplify the diagram, these contacts are shown in their natural locations in the circuit, and are numbered 1 to 9 inclusive for the purpose of identification. In series with the winding 161 is the reading condenser arrangement comprising condenser 162 and shunt resistor 163. The purpose of the reading condenser arrangement, as is well understood in the art, is to provide a strong oper-

ating pulse in the circuit followed by a lower holding current. It also compensates in part the inductance of the circuit of which it is a part.

5

Synchronization

Referring to Fig. 2, the transmission of synchronizing impulses is accomplished as follows:

- Assume that the brush arm 13 is frictionally driven, but is held in the rest position on segment 10 3 by the armature 16 of the relay 15. To start sending synchronizing signals, the send-receive switch 190 is thrown to the S position, as indicated. This completes a circuit from zero bus thru reading condenser 162 thru winding 161 of 15-multiple switch relay via contacts 191-192 of send-receive switch to relay 15, thru condenser 22 and winding 20 to positive bus. A strong current thru this circuit operates multiple switch relay 160, breaking contacts 2-3, 5-6, 8-9 and 20 making contacts 1-2, 4-5, 7-8. Release relay 15 is also energized, attracting armature 16 which releases brush arm 13. As condensers 22 and 162 become charged, a small steady current limited by resistor 163 flows thru windings 161 and 21 25 providing sufficient holding current to hold the multiple switch relay and release relay in the operated condition. A strong operating pulse followed by low holding current is thus provided, preventing over heating of the relay windings.
- 30 On being released by armature 16, the brush arm 13 is set in rotation by the friction drive, and takes up the uniform speed of the drive shaft set by the driving motor. When the brush arm reaches segment 1, a circuit is completed 35 from positive bus via contacts 8-7 thru the pulse shaping net-work comprising the reading condenser 165 and shunt resistor 166 and inductance 167 in series therewith, via contacts 4-5 to segment 1, via brush arm 13 to ring 12, via contacts 40 2-1 thru primary 28 to zero bus. For the duration of the contact of the brushes with segment 1, current flows thru the circuit just traced, and a corresponding signal impulse is sent to the line by the secondary 29 of the output transformer 27.
- 45 This impulse, which is repeated for each revolution of the brush arm 13, is called the synchronizing signal.

It is to be noted that the synchronizing signal in its passage to the line from secondary 29 50 passes thru primary 33 via the center tap, and thus thru the equal sections of primary 33 to the line terminals. With the artificial line A. L. in proper balance the currents thru the sections of primary 33 are equal, and in opposition, hence 55 no voltage is induced in the secondary 34 and the grid 133 is unaffected by signals sent to the line under these conditions.

Referring to Fig. 3, the reception and application of the synchronizing signals at the receiving 60 station is as follows:

At the receiving station, the synchronizing signals are received at the line terminals 30 and 31 and are applied to the terminals of primary 33 of the input transformer 32. The current from 65 terminal 30 passing thru the secondary 29 of the output transformer and the center tap branch of primary 33 is negligible.

The synchronizing signal thru primary 33 induces a voltage across secondary 34 and shunt 70 resistor 35, which with proper polarity of the line terminals, opposes the bias voltage on grid 133. The potential of grid 133 is thus made more positive, and at a critical value depending on the characteristics of the relay 132 and the plate voltage 75 age thereon, relay 132 becomes ionized and con-

ducting, and current flows in the plate circuit. The brush arm 13 being at rest on segment 3, a circuit is completed from zero bus thru center tap 136, and transformer winding 137 thru cathode 134 to plate 135 via contacts 173-174 thru winding 171 via contacts 194-195 of the send-receive switch and contacts 3-2 to ring, via brush arm 13 to segment 3 via contacts 17-18 thru condenser 22, thru winding 20 to positive bus. A strong current pulse flows thru this circuit, 10 operating release relay 15 and thereafter cut-off relay 170, which opens contacts 173-174, terminating the pulse. The armature 16 is pulled in, releasing the brush arm 13, and opening contacts 17-18. The flow of current thru condenser 15 22 has charged that condenser providing holding current for the high impedance winding 21, delaying the release of armature 16. The cut-off relay 170 releases quickly, being of low impedance, and being shunted by the resistor 172. Before 20 relay 170 closes its contacts, however, the plate current has been interrupted long enough to permit the electronic relay 132 to de-ionize and the grid 133 to regain control. The electronic relay 132, with its associated cut-off relay, thus provides strong local current impulses which are initiated by the line signals, but which are of definite duration.

When released, the brush arm 13 is set in motion by its friction drive (and clutch as is explained hereinafter) and is thereafter rotated at uniform speed. Brush arm 13 having started from segment 3 shortly after the brush arm at the sending station passed segment 1, would arrive at segment 1 before the arrival of the next 35 synchronizing signal from the sending station, were it not for a slight delay in the operation of release relay 15 and the clutch mechanism.

Because of these delays which occur only during the first revolution, the lead provided by 40 starting the brush arm from rest on segment 3 enables the brush arm to arrive at segment 1 as the next synchronizing signal is received. The synchronizing signal energizes the electronic relay 132 as before, but this time the circuit is completed via segment 1 as follows: via same circuit 45 as before to ring, via brush arm to segment 1, via contacts 5-6, thru winding of corrector magnet 36, thru condenser 22 and winding 20 to positive bus. The current pulse thru this circuit 50 replenishes the charge on condenser 22, maintaining the release relay 15 in the operated condition, and energizes the corrector magnet 36. The details of the operation of the corrector magnet 36 and release relay 15 will be more 55 fully described hereinafter. At this point it is to be observed that provided the brush arm 13 arrives on segment 1 when the synchronizing signal is being applied to the grid of the electronic relay, the charge on the condenser 22 is 60 replenished, sustaining the operation of the release relay 15, and the corrector magnet 36 is energized. If these conditions are not fulfilled, release relay 15 drops out, and during the subsequent revolution the brush arm 13 is stopped on 65 the rest segment. If the signals continue, the same procedure is repeated until synchronization is established.

In practice, it is found that with proper adjustment of the clutch mechanism and by setting 70 the rest position for the brush arm at the proper place, synchronization is usually established on the first revolution. Thereafter, synchronization is maintained by the corrector magnet correcting the phase angle of the receiving distributor arm 75

to keep it in unison with the sending distributor arm. Should, for any reason, unison within approximately one half segment width be departed from, the brush arm 13 is stopped on the 5 rest segment by reason of release relay 140 dropping out, and the synchronizing procedure is repeated when the next synchronizing pulse is received. Thus synchronism, if lost, is automatically re-established.

10 *Sending circuits and operations*

Referring to Fig. 2, the printing signal impulse transmitting apparatus includes the key switches 157 of break-make type, one for each key of the 15 typewriter, there being 49 keys on a standard typewriter key board. The armature spring of each key-switch is connected to an individual segment; the make springs are connected to the common key-switch bus 138, as shown. The key 20 switch bus is connected to one terminal of the non-repeat relay 140, and to spring 144 of relay 140.

Each key lever operates its associated key-switch by means of an insulated push rod 150 25 as indicated. For transmitting purposes, each key lever when depressed is held down by the universal bar key latch 151 until released by the key release magnet 152. The universal bail 153 is positioned below and transversely across the row of 30 key levers, being held in light contact therewith by a retractile spring (not shown). When any key is depressed, the bail 153 closes the auxiliary switch 154 by means of push rod 155. One spring of the auxiliary switch is connected to the key-switch bus 138; the other spring is connected to 35 spring 142 of non-repeat relay 140.

The non-repeat relay 140 has a low impedance winding 145, located on the heel end of the core 140, and a high impedance winding 147. In series 40 with the winding 147 is a reading condenser arrangement consisting of the condenser 148 and shunt resistance 149.

To commence sending, the send-receive switch 45 is thrown to the S position, and synchronizing signals are sent to the line for a few seconds to permit the receiving machine to come to synchronization as described above. Printing signals may then be sent by depressing the typewriter keys as for ordinary typing.

50 Assuming key 5 to be depressed, the operations which result are as follows: As the key lever nears the bottom of its stroke, the mechanism of the typewriter is tripped, and the typewriter immediately types the selected character to furnish a 55 local copy of the message. The key lever is latched down in the depressed position by the universal bar key latch 151 hooking over the end of the key lever 156. The finger can be at once removed from the key. When the key is pressed 60 down, the push rod 150 (one for each key lever) which abuts against the lower edge of the key lever, pushes down the armature spring of its associated key switch, breaking the upper contacts and making the lower contacts. The universal bail 153 is also rotated about its axis by the movement of the key lever, and operates the single push rod 155 which closes the auxiliary switch contacts. The operation of the key switch connects the key switch bus 138 to the segment 65 associated with the particular key switch, in the present instance segment 5. When the brush arm 13 arrives at segment 5, a circuit is completed from positive bus, via contacts 8-7 thru low impedance winding 146 of non-repeat relay 70 140, via contacts 144-145 to key switch bus 138,

via middle and lower contacts of the operated key switch to segment 5, via brush arm 13 to ring, via contacts 2-1 thru primary 28 of output transformer 27 to zero bus 131. A strong current impulse flows thru this circuit, its duration being 5 determined by the time of contact of the brush arm 13 with segment 5, and a printing signal of the same duration is sent to the line by the secondary 29 of the output transformer 27.

10 *Non-repeat and key release arrangement*

The local current impulse just described, in addition to sending a printing signal to the line, also performs an important part in the non-repeat and key release actions. The local current pulse thru winding 146 of non-repeat relay 140, together with the part of the pulse flowing thru the high impedance winding 147, operates non-repeat relay 140, thus opening contacts 144-145, and closing contacts 144-143, and 20 142-141. Opening contacts 144-145 cuts off the winding 146. Closing contacts 144-143 connects one terminal of the key release solenoid 152 to the key switch bus 138 and to winding 147. Closing contacts 142-141 connects the zero bus 131 25 to the upper spring of the auxiliary switch and thru its contacts places zero potential on the key switch bus 138. Any connected segment, except the synchronizing segment, is therefore likewise placed at zero potential and no more printing 30 signals can be sent to the line. This constitutes the non-repeat feature.

Closing contacts 142-141 also completes a circuit from negative bus via contacts 141-142, via contacts of the auxiliary switch, thru winding 35 147 and reading condenser 148 via contacts 8-7 to positive bus. Current thru this circuit re-energizes non-repeat relay 140 and supplies holding current therefor. A second circuit is completed from positive bus via contacts 8-7 thru 40 the winding of the key release solenoid 152, thru reading condenser 148 via contacts 143-144, via auxiliary switch contacts, via contacts 142-141 to zero bus. A current pulse thru this circuit energizes the key release solenoid 152, whose 45 plunger pulls the key latch 151 away from the key levers by means of the extension 182 as shown.

If the finger is removed from the freed key, the key lever is drawn up by its retractile spring and the springs of the auxiliary switch 154 lift 50 the push rod 155 and open the contacts.

Opening these contacts breaks the circuit to zero bus via contacts 142-141, and takes the holding current from the non-repeat relay 140 and key release solenoid 152, which thereupon release. Zero potential is also removed from the key switch bus 138 and any connected segment. When the key release solenoid 152 releases, the key latch 151 is returned to an engageable position by the retractile spring 183. When the non-repeat 60 140 releases, contacts 141-143 and 143-144 are opened, and contacts 144-145 are closed, restoring initial conditions.

It is to be noted the non-repeat relay 140 and key release solenoid 152 are not released until the 65 contacts of auxiliary switch 154 are allowed to open. Consequently, should a key be deliberately held down, repeat signals are not permitted to be sent to the line, and the key latch is held out of engagement until the key is released. The result is that only one signal can be sent to the line for each depression of a key, and the time a key is held down is of no consequence as regards the operation of the apparatus nor as regards the accuracy of transmission. In normal operation 70 75

the keys are depressed and released quickly by the operator, and are released by the key-release solenoid practically instantaneously when the printing signal is sent to the line.

5 *Key interlock*

It will be apparent from the foregoing description of sending operations, that a variable interval intervenes between the closing of a key 10 switch and the collection of the impulse from the connected segment by the distributor brush. This interval depends on the speed at which the distributor rotates and the angular travel of the brush arm in order to reach the connected segment, the interval being always less than the time of one revolution.

It is manifest that if two keys were pressed simultaneously, or almost simultaneously, the distributor would send out a printing signal from the 20 first connected segment, whether or not this was the proper order for transmission. To eliminate errors of this kind, a key interlock is provided which permits only one key at a time to be depressed. While various forms of interlock have 25 been devised and employed, the preferred form is shown in Figs. 22 and 23. This form of interlock is well known, and its operation being familiar to those current with the art, detailed description is not required.

30 The principal parts of the interlock are the comb 235, the roller race 234, and the rollers 236, one for each key lever plus one. Each key lever is located in an individual slot in the comb 235 as shown. The diameter of the rollers is exactly 35 equal to the key space centers, and the space between all the rollers combined is slightly greater than the thickness of a key lever 156. As indicated in Fig. 22, when one key lever is depressed, the slots for all the rest of the key levers 40 are blocked.

Dual space segment arrangement

With a single impulse system as herein described, the duration of the signal impulse is determined by the number of segments on the distributor and the speed of rotation of the distributor arm. 45

There is a practical lower limit to the duration of the signal impulse, since the shorter the impulse, the higher the required frequency characteristics of the transmission system connecting the sending and receiving stations. As is well known, all communication systems have definite limits as to frequency characteristics, the limits 50 being particularly restricted on telegraph cable circuits. One of the limitations on the speed of operation of printing telegraph systems is therefore the length of the signal impulses and the 55 number of segments on the distributor and the speed of rotation of the distributor arm are subject to this and other limitations.

One of the features of the present invention is the means by which the number of words transmitted in a given time is increased without 60 a material shortening of the signal impulse. An average word in telegraphic practice consists of five letters and a space, and the speed of transmission is rated on the basis of the number of equivalent average words sent per minute. On 65 the average, since a space occurs for every five letters, one sixth of the signals are space signals. In the present invention, means are provided whereby the average time required to collect and transmit a space signal is approximately one half that required to collect and transmit 70

other printing signals. The means is to provide two segments for the space signal located approximately diametrically opposite on the distributor. These segments are connected in parallel, and either one can transmit or receive a space signal. The arrangement is indicated by the connection of segments 8 and 36 in Fig. 1A. Thus, when the space bar is depressed, the distributor arm on the average moves only one quarter revolution until the signal is collected; for other signals an average movement of one half a revolution is required. As an example of the advantage of this improvement, assume that the distributor arm makes 4 revolutions per second. The theoretical average speed of transmission, using only one space segment, would be: 15

$$\frac{4 \times 60}{(6 \times \frac{1}{4})} = 80$$

words per minute. Using the dual space segment 20 arrangement, the theoretical average speed would be:

$$\frac{4 \times 60}{\frac{1}{2} + \frac{1}{4}} = 87$$

words per minute (approx.). 25

Sine wave impulse feature

As is well understood, a sine wave impulse undergoes the minimum distortion in transmission, and permits the design of circuits of minimum impedance for a given frequency. Also, the problem of suppressing sparking at contacts is rendered less difficult. One of the features of the present invention is means whereby virtual sine 30 wave impulses are generated in the local circuits, and the signals sent to the line are of approximate sine wave form. In the sending circuit, the means for forming sine wave impulses comprise the storage condenser 186 across the voltage 35 divider 24a and in series with section 24b, together with wave shaping arrangements and proper design of the circuit constants of inductance, resistance, and capacity. In the sending 40 circuit connected to segment 1 for generating synchronizing impulses, the wave shaping arrangement comprising the reading condenser 165 and shunt resistor 166, and inductance 165, in series therewith, together with the storage condenser 186 and the primary 28 of the output 45 transformer 27, co-operate to produce a sine wave impulse in this circuit, and virtual sine wave 50 synchronizing signals are sent to the line. In the printing signal circuits, the storage condenser 186, the reading condenser 148, windings 55 146 and 147 of non-repeat relay 140, and the primary 28 co-operate to produce sine wave impulses in these circuits. 55

Receiving circuits and operations

Synchronism having been established as previously described, and the brush arms at the receiving and sending stations being in unison, printing signals may be sent to the receiving station as described in connection with sending operations. 65

Referring to Fig. 3, the printing signals when received are impressed on the primary 33 of the input transformer 32, and potential variations from the secondary 34 cause a drop across resistor 35 opposing the negative bias on grid 133 which on becoming sufficiently positive triggers off the electronic relay 132, which becomes conducting. A circuit is thus completed from zero bus 131 thru center tap 136, and winding 137, 70 75

from cathode 134 to anode 135, via contacts 173-174 thru winding 171, via contacts 194-195, via contacts 3-2 to ring, via brush arm 13 to the particular segment with which the brushes of distributor arm 13 are in contact. From this segment, of which segment 5 may be considered as an example, the circuit continues via the middle and upper contacts of key switch 157 to winding 159 of key magnet 158 to key magnet bus 139, thence via contacts 8-9 to positive bus 25. The pulse thru this circuit energizes cut-off relay 170 and key magnet 158, whose plunger is attracted, stretching spring link 184 which pulls down the key lever to which it is attached. The key lever trips the typewriter mechanism (not shown) and the character is printed. As the key lever nears the end of its downward travel, the push rod 150 breaks the middle and upper key switch contacts. Owing to the inductance of the key magnet, the inertia of the plunger and the key lever, and the action of the spring link 184, the breaking of the key switch contacts is retarded and the circuit is actually broken by the opening of the contacts 173-174 by the cut-off relay 170. The length of the printing impulses and the synchronizing impulses is thus determined by the setting of the cut-off relay 170, and this relay is in practice adjusted to cut-off shortly before the termination of the line signal.

In this way, the circuit is normally broken at contacts 173-174, which may be provided with a spark suppressor arrangement to suppress sparking at these contacts. With perfect unison, the circuit is broken before the brushes leave the connected segment, hence sparking at the distributor is minimized, such sparking as occurs being principally due to the inductive energy in the key magnet. The sparking at the contacts of the key switches is negligible.

It is to be observed that when receiving printing signals, the key magnet energized is that which is connected to the segment being contacted by brush arm 13. When the brush arms at the sending and receiving stations are in unison, the key magnet selected at the receiving station will correspond with the key switch closed at the receiving station. Accuracy in selection thus depends on close unison of the brush arms, and cutting off the printing impulse before the brush arm at the receiving station has carried over into contact with the adjacent segment. The corrector magnet provides the required close unison, and the cut-off relay terminates the impulses, both synchronizing and printing, after a definite interval. The cut-off relay thus enables the printer mechanism to clear one operation before a succeeding operation is initiated. The line retardation and ionizing time of the electronic relay are not material factors with the present invention, since the synchronizing signals are subject to the same delay as are the printing signals, and the corrector magnet automatically compensates for this delay. Likewise, any instrumental delays from line relays, etc. interposed in the transmission system are automatically compensated for.

While for illustrative purposes, the sending and receiving stations are represented as being connected by a transmission line consisting of one wire and ground, it is to be understood that any form of communication system, such as telephone, telegraph, or radio or cable circuits may be used, automatic compensation of transmission delays provided by the invention being an

important factor in its ready adaptation to various forms of communication circuits.

Calling circuits and operations

Referring to Fig. 4, which shows the calling circuits separated from the other circuits, the apparatus receiving the calling signals from the line include the artificial line A. L., and the primary 33 of the input transformer 32. The apparatus for utilizing the calling signals comprise the secondary 34 of the input transformer, the glow lamp 202, the electronic relay 132, the cut-out relay 170, the send-receive switch 190, and the call bell 201. The send-receive switch 190 controls the calling circuit. When the send-receive switch is in either the "typing" or "sending" positions, the call bell is connected in the calling circuit; when the send-receive switch is in the "receiving" position, the call bell is disconnected.

Assume that the send-receive switch at the receiving station is in the typing position and that the machine is being used for typing purposes. To call, the sending station throws the send-receive switch to the S position and sends synchronizing signals to the line as described under synchronization. From terminals 36-31 of the receiving station, the signals traverse the circuit from terminal 30 thru primary 33 thru artificial line A. L. to terminal 31. Some current flows thru secondary 29, but the primary 28 is open, and this current is ineffective. The signal impulses thru the primary 33 induce potential variations in the secondary 34 and these variations are applied to the grid 133 as previously described. The grid 133 ionizes the electronic relay 132 which becomes conducting, and a circuit is completed from zero bus 131 thru electronic relay 132 via contacts 173-174, thru winding 171 of cut-off relay 170, via contacts 194-195 thru winding of the call bell 201 to positive bus 25. Current flowing in this circuit energizes the call bell, and also cut-off relay 170, which operates and breaks the circuit in the usual way. This action is repeated as each synchronizing impulse is received. Since the cut-off relay opens the circuit after each pulse, the interrupter in the bell can be dispensed with.

To stop the bell, the send-receive switch is thrown to the receive position which opens the calling circuit, and establishes the receiving circuit as shown in Fig. 3. The receiving distributor is then synchronized, as previously described, and transmission begins.

The second calling situation is that existing when a station is sending and the receiving station wishes for some reason to call back. This is the so called "break-in" call. Referring to Figs. 2 and 3, the circuit conditions at the sending station are shown in Fig. 2, those at the receiving station in Fig. 3. To make the break-in signal, the receiving station throws the send-receive switch to the send position, changing its circuit conditions to those shown in Fig. 2, and synchronizing signals are immediately sent to the line in the reverse direction, i. e. from receiving station to sending station. The calling circuit at the sending station is in the condition shown in Fig. 4, the send-receive switch being in the position shown by dotted lines. Due to the duplex arrangement of the transformers, previously described, the received synchronizing signals actuate the electronic relay 132, and the call bell is energized as previously described. Due to the

balancing effect of the artificial line, the outgoing signals do not actuate the electronic relay.

Without further analysis, it will be evident that a called station can acknowledge the call, and signal ready, by throwing the send-receive switch momentarily to the send position in answering a call, and before moving to the receive position. The calling station is thus informed of the readiness of the called station, and can start sending

10 without delay.

In the foregoing, the call signal device was described as a bell. It is obvious, however, that any of the usual audible or visual signalling devices, such as buzzers, gongs, annunciators, lamps, etc.

15 can be employed, the power in the calling circuit being adequate for operating such devices and such variations are included within the scope of the invention as defined by the generic claims.

20 It will be observed that in the foregoing description of the calling system, two way communication circuits were assumed. When one way circuits, such as radio circuits, are employed, break-in and call-back signals are not usually 25 feasible and the usual calling conventions for one way circuits must be observed.

It is further to be observed that with the calling system described, it is not necessary that the distributor motor be turned on, but that 30 power must be supplied to the electronic relay. To receive a calling signal without having power on the electronic relay, a small neon glow lamp 202 is connected into the calling circuit at some convenient point, as for example across the secondary 35 as indicated in Fig. 4.

It will be perceived that I have provided a simple and flexible calling system which is very economical in cost, and which possesses numerous advantages.

40 *The electronic relay*

The electronic relay 132 may be of the hot-cathode type, as shown, or of the cold cathode type, in which case the cathode heating trans- 45 former 137 is not required. As is well known, the grid potentials sufficing to ionize electronic relays is comparatively low, and they are therefore susceptible to stray potentials, inductive effects, etc. and for best results, measures to insure 50 stability in operation are desirable. In the present invention, stabilizing measures which have been found effective comprise the grid current limiting resistor 203, the grid to cathode by-pass condenser 204, and the grid potential 55 stabilizer arrangement consisting of the ballast condenser 205 and the ballast resistor 206.

The function of the current limiting resistor 203 is to limit the grid current to moderate amounts during the periods when the grid is positive. It is preferably of a comparatively high value, values of 50,000 to 500,000 ohms giving good results. The function of the grid to cathode by-pass condenser 204 is to by-pass high frequency and inductive potentials, preventing ionization of the relay from these effects. This condenser may be of comparatively small size, capacities of the order of .0025 mfd. having been found to give good results.

The function of the ballast condenser 205 and ballast resistor 206 is to preserve uniform bias potentials on the grid 133. When local impulses occur, part of the charge on storage condenser 186 is lost, and current flowing thru bias resistor 245 to replenish the charge on condenser 75 186 causes a momentary variation in drop across

24b. The potential across ballast condenser 205, and consequently the grid bias potential, remain almost constant during such variations, since because of ballast resistor 206, any change in the charge on condenser 205 is retarded. The time 5 constant of the combination of condenser 205 and resistor 206 is proportional to the product of their values, hence a wide range of values is possible. The arrangement permits an electronic relay to be operated from a voltage divider of 10 momentarily fluctuating voltage with practically the same stability as is obtained with a battery to supply bias to the grid of the relay.

The rotary distributor and phase corrector

15 In Figs. 5 and 6, which show in detail the rotary distributor and corrector magnet assemblies, the rotary distributor is seen to consist of a hub 31, with diametrically positioned contactor arm 38 and corrector arm 39 mounted in cross holes 40 therein by suitable holding means such as set screws 41. On the contactor arm 38 is mounted a link 42 of insulating material by means of screw 43, extending axially into the outer end of contactor arm 38. On the projecting end of link 42 is mounted the brush arm 13 by means of a screw 44, extending axially into arm 13. The outer end of the arm 13 is cut into half-cylindrical section, and on the cut section is mounted the half-cylindrical brush clamp 30 45. Between the flat surfaces of arm 13 and clamp 45 are clamped two flexible metallic brushes 46 by means of a screw 47. The outer ends of the brushes 46 slope rearwardly and contact the segments 11 and ring 12 with a light 35 pressure. The brushes are conveniently made of copper braid, bundles of small copper wires, or silver strips, as is commonly practiced in the telegraphic art.

The corrector arm 39 carries at its outer end 40 the corrector bar 49 of magnetic material, preferably a metal or alloy of low magnetic permeability such as soft pure iron, or magnetic nickel alloy. The corrector bar may have a variety of shapes, the preferred shape being 45 shown in Figs. 6 and 7. The corrector bar should be rigidly mounted on the corrector arm, and is so mounted conveniently by positioning in a slot cut in the end of the corrector arm, and secured therein by one or more screws 48 (one being shown) as clearly indicated. In the preferred form, the location and length of the corrector bar 49 is such that on rotation of the distributor hub, the corrector bar passes end-wise between the pole pieces 50 with a small air-gap 55 at each end. The air-gap which has been found preferable is of the order of .025 inch.

The corrector magnet 36 is preferably mounted on a bracket 52, adjustable in an arc by means of curved slots 53 and screws 54, so that the poles 60 50 of the corrector magnet 36 may be adjustable sidewise concentrically with the drive shaft 55. By this adjustment, the corrector magnet 36 may be moved in relation to the synchronizing segment 1. The need for this adjustment 65 will be evident when it is considered that a small interval of time is required for the flux in the corrector magnet 36 to build up in response to the synchronizing current impulses, this interval in part depending upon the inductance in the corrector magnet circuit. During this small interval, the distributor arm moves in the direction of rotation, hence the corrector magnet for proper action should be displaced angularly in the same direction by a slight amount in excess 75 70 75

of the mechanical angle of 180° represented by the axis of the corrector arm and the line of contact of the brushes 46. The best adjustment of the position of the corrector magnet 36 is 5 readily determined by trial and may thereafter be left fixed.

The best proportions for the faces of the poles of the corrector magnet, and for the corrector bar, may be in part determined by analysis, but 10 refinement in the design of these parts is most readily obtained by experiment. The result desired is that the corrector bar should pass between the poles of the corrector magnet without material retardation or acceleration when the 15 distributor arm is in perfect synchronism with that of the sending station, but shall be subject to corrective action when the synchronous relation is departed from.

Figs. 8 and 9 show a modification of the corrector bar-corrector magnet arrangement, in 20 which the corrector bar 49 passes in front of the poles 50 of the corrector magnet 36. The poles 50 are in this case narrowed at the face nearest the corrector bar to substantially the width of 25 the corrector bar, as shown. On analysis, it will be evident that as the corrector bar approaches or departs from the poles 50, a tangential magnetic pull will be exerted. The correcting action will therefore be the same as for the forms shown 30 in Figs. 6 and 7. The strong radial pull, however, requires increased rigidity for the drive shaft, to resist this unbalanced pull. This unbalanced radial pull, together with the fact that the corrector bar 49 of the form shown in Figs. 35 8 and 9 is for the same magnetic efficiency heavier than that shown in Figs. 6 and 7 represent comparative disadvantages for the first named type.

Another possible modification of the form of 40 the corrector bar and corrector magnet poles is shown in Figs. 10 and 11. Since this modification represents a combination of those previously discussed, its action is manifest and further discussion is unnecessary.

45 Various other combinations of pole pieces and corrector bar shapes are possible, and such variations are included within the scope of the invention as defined by the generic claims.

Fig. 12 shows a typical tangential magnetic 50 pull-displacement curve. The ordinates represent, in arbitrary units, the tangential component of the magnetic attraction of the poles 50 on the corrector bar 49 shown in Figs. 6 and 7. The abscissae represent the displacement of the vertical median plane of the corrector bar from the median plane of the corrector magnet poles. 55 The arrows within the diagram indicate that the pull is towards the median plane of the corrector magnet. From this curve it is evident that a tangential force tends to hold the corrector bar in alignment with the corrector magnet poles. Assuming the corrector magnet to be energized by uniform direct current, this force depends on the amount of the displacement of the corrector 60 bar from the median plane of the corrector poles, increasing rapidly to a peak value and then declining. For exact coincidence of the median plane of the corrector bar with that of the corrector magnet the tangential force disappears. 65 This region in the curve is termed the "notch" and clearly indicates the nature of the corrective action of the corrector magnet. The curve shown is a static curve at a particular value of 70 current. Other values of current produce a fam-

ily of curves of the same general form. When the corrector bar is passed rapidly between the poles, some distortion of the curve doubtless occurs. Also, the synchronizing current impulse is of a general sine-wave form, causing a rise 5 and fall in the magnetizing force of the magnet. Practical experience indicates, however, that the curve shown in Fig. 12 represents substantially the corrective action of the corrector magnet on the corrector bar to maintain the latter in unison 10 with the sending distributor arm.

Referring to Fig. 6 which shows details of the drive-shaft hub assembly, the hub 37, preferably made of a light metal such as aluminum, has a cylindrical axial bore 56 fitted to give a free turning fit on the drive shaft 55. A drive collar 57 is fixed on the drive shaft 55 by suitable adjustment means such as the set screw 58. To the periphery of the collar 57 is cemented or vulcanized a rubber roll 59. Next is placed over the 20 drive shaft a washer 61, preferably of steel. Upon this washer rests the hub collar 62, to which is cemented or vulcanized the rubber roll 63. The hub collar 62 has an upwardly extending annular section which extends into a counter-bored cylindrical cavity in the lower end of the hub 37, and is adjustably secured therein by any preferred means, as by the set screw 64. Assembled on the hub collar 62 next to the hub 30 is the stop flange 65, being secured thereto by welding or other preferred means. The stop flange is extended radially at one point on its periphery to form an ear 66 as shown. The purpose of this construction is to permit of ready 35 angular adjustment of the ear 66 on the stop flange 65 in relation to the distributor arm to enable proper setting of the rest position of the brushes 46 to be made.

To the top of the hub 37 is demountably assembled the friction cup 67, held from rotating 40 by a sliding pin and hole arrangement (not shown). The upper portion of the friction cup is counter-bored to contain a friction pad 68 of soft material, preferably a firm felt ring. The upper end of the drive shaft 55 is reduced in section, and is threaded. Thereon is screwed the adjustable friction nut 69, provided with a radial set screw 71 to retain the friction nut in the position of adjustment.

The friction pad 68 is liberally oiled and on 50 being compressed, oil works down the shaft along the bore of the hub to the friction washer 61 to provide lubrication of these parts. The friction nut is adjusted until the distributor arm is driven with little if any slip. The arrangement 55 shown permits of an easily adjustable, smooth acting friction drive for the distributor arm which is found to stay in adjustment for extended periods.

The clutch mechanism

Referring to Figs. 13, 14, 15 which show the assembly of mechanism by which synchronism is established, adjacent to the rolls 59 and 63 and 65 with axis parallel with the shaft 55 is rotatably mounted the double cam 72 located so as to engage circumferentially the rolls 59 and 63. The cam 72 rotates on the spindle 73 mounted perpendicularly on plate 74 by riveting. Underneath the cam 72, slidably mounted on plate 74, is the cam detent 75. The cam detent 75 pivots at one end on the pivot pin 76. In the middle section of the cam detent is a curved slot 77, through which extends the stud screw 78. This 75

screw prevents the cam detent from rising out of place and limits its travel. The free end of the cam detent is bifurcated, and the two prongs turned up to form pawls 80 and 81 which alternately engage the lower stop 82 on the double cam 72. Extending thru the cam detent 75, between the slot 77 and the pin 76, is located a small hole 83, thru which is assembled the crank-shaped end of the operating link 84. The other end of link 84 is threaded and to it is assembled the adjustable clevis 85. The clevis 85 is assembled to the armature 16 of the release relay 15 by a pin 86.

The cam 72 is provided with a projecting upper stop 87, located on the top surface, and diametrically opposite the lower stop 82. This upper stop 87 is engageable by the ear 66 of the stop flange 65 in one position of the cam 72. The diameter of the cam 72 is reduced at the middle by the groove 90 (see Fig. 16). Extending into and across the groove 90 is the accelerating spring 91 which bears near its outer end against the accelerating pin 92, as shown. The accelerating spring 91 is looped in several turns around a pin 93 rigidly mounted in the plate 74. The fixed end 94 of the accelerating spring 91 bears against the pivot pin 76. The accelerating pin is so formed that when assembled as shown, the free end bears with moderate pressure against the accelerating pin 92.

The circumference of the double cam is serrated with a straight knurl except over an arc of approximately 90° in the region of the upper stop 87, where the radius is reduced and the cam edges are left smooth. This arc of the cam clears the rolls 59 and 63 when adjacent thereto.

The operation of the clutch mechanism is as follows: When the parts of the mechanism are in the position shown in Fig. 13, the short pawl 80 engages the lower stop 82, stopping the double cam in such position that the upper stop 87 is virtually on the line of centers of the rolls 59 and 63 and the double cam 72. In this position the smooth edge of the cam is adjacent the rolls 59 and 63, providing clearance therebetween. The hub 37 can therefore continue rotation until the ear 66 engages the upper stop 87, which stops the motion of the hub and the brush arm 13 is stopped in the rest position on segment 3 as shown in Fig. 5. Since the hub 37 is frictionally driven, the drive shaft 55 and the roll 59 continue in rotation.

Assuming now that the release relay 15 is energized, the armature 16 pulls the link 84 which in turn draws the cam detent 75 away from the cam. The short pawl 80 is thus pulled out of engagement with the lower stop 82, releasing the cam 72. The detent 75 is drawn to the position shown in Fig. 14. The accelerating spring 91 by exerting force on the accelerating pin 92 causes the cam 72 to rotate quickly in a counterclockwise direction. This rotation of the cam 72 brings its serrated edges into engagement simultaneously with rolls 59 and 63. Since roll 59 is secured to the drive collar 51, and roll 63 to the hub collar 62, when the cam serrations grip the rubber rolls 59 and 63, the hub 37 is virtually locked to the drive shaft. It is to be noted that this is not a friction clutch, since the serrated cam edges mesh with the rolls 59 and 63 without slipping and as tho geared thereto.

The cam 72 is rotated by reason of being engaged by roll 59, and the upper stop 87 is rotated away from the ear 66, removing these members

from engagement. The cam 72 continues to rotate until it reaches the position shown in Fig. 14, when the lower stop 82 comes into engagement with the long pawl 81, stopping the cam. In this position the smooth arc is adjacent the rolls 59 and 63 and the hub 37 is freely driven by the friction drive previously described. The ear 66 passes clear of the upper stop 87 as shown in Fig. 14.

Should the release relay 15 become de-energized, the armature 16 is pushed back by spring 17, and link 84 pushes the detent 75 back into the position shown in Fig. 13, disengaging pawl 81 and lower stop 82. The accelerating spring 91, which has been placed in tension on the accelerating pin 92 by the rotation of cam 72, now rotates cam 72 thru a short arc, bringing cam 72 in the position shown in Fig. 13. When the ear 66 arrives at the upper stop 87, the hub is stopped and conditions are restored as at the beginning of the cycle described above.

It is to be observed that the mechanism just described provides a definite, but adjustable, stop or rest position for the brush arm 13; that on operation of the release relay 15 the driving shaft 55 and hub 37 are quickly clutched together in a positive manner to bring the hub 37 up to the speed of the drive shaft; that the positive action of a gear clutch is obtained without the difficulty of possible clashing of gears if engaged in the wrong position; and that the clutch action is controlled with the application of but little force on the part of the clutch release magnet. The accelerating spring 91 minimizes the interval required for the clutch to act after the release relay is energized.

It is obviously possible to eliminate the clutch mechanism and cause the link 84 to engage and stop the ear 66 without the intervention of additional mechanism. The frictional torque of the friction drive is, however, restricted to a small amount, otherwise the pull of the corrector magnet 36 will be insufficient to overcome the frictional torque. The proper frictional torque for good correcting action is incapable of accelerating the hub 37 and the distributor arms mounted thereon without considerable slip occurring. Furthermore, in practice it is found that such slip during acceleration is variable to such an extent that the corrector arm bar 48 does not reliably come into position between the poles 58 when the hub is accelerated solely by the normal frictional driving torque. The object of the clutch mechanism is therefore to establish synchronization in a single revolution in a certain and reliable manner.

The release relay

Referring to Figs. 13 and 17, which show the release relay 15 and associated parts of the circuit, comprising part of the present invention, the relay proper is of a well known type, commonly referred to as a telephone relay. On the core 15 is assembled a low resistance coil 20 of a comparatively few turns concentrated at the armature end of the core. Next in order is a high resistance winding 21 of several thousand turns, occupying the central part of the core length. At the heel end of the core is assembled a concentric sleeve or "slug" of copper 23. The coils 20 and 21 are wound in the same direction and the adjacent terminals of the windings are connected together in series connection.

The release relay as thus far described is a well known type commonly classified as a double-

wound slow releasing relay. When supplied with a pulse of sufficient magnitude and of considerable duration, such relays normally operate in from .004 to .006 second, and release in from .08 to .28 second after being fully energized. In high speed printing telegraphs, however, the signal impulses are of very short duration, the complete pulse interval being of the order of .003 to .005 second. A relay of the usual type designed to have a release time of .25 to .30 second, i. e. the time required for the distributor arm to make one revolution, plus a margin, will not respond to impulses of short duration, for the reason that the copper slug required to produce such delay in release time is of comparatively large size, and prevents by its reaction the storing of the required amount of magnetic energy in the magnetic structure of the relay. To overcome this difficulty, which is inherent with this type of relay, a storing condenser 22 is connected in shunt across the terminals of the high resistance winding 21. This condenser should normally be of considerable capacity, values of from 2 to 16 microfarads, depending on the release time desired, having been found to give good results. With this condenser added to the combination, the operation of the release relay 15 in response to current impulses of short duration is as follows: When the synchronizing pulse is applied to the circuit shown in Fig. 17, a rush of current flows thru the low resistance coil 20 into the storing condenser 22, which because of its large capacity offers comparatively little impedance to such rush of current, particularly at the beginning. This rush of current thru coil 20 magnetizes the core 15 at the armature end and attracts the armature 16. The reaction of the high resistance coil 21 and the slug 23 are ineffective to prevent the coil 20 from magnetizing the armature end of the core 15, because of their remoteness from this section of the core, and because of the high inductance of the coil 21. The counter E. M. F. generated by transformer action in coil 21 by the current in coil 20 does not oppose the current in coil 20, but is utilized to aid in charging condenser 22. The maximum energy is thus stored in the charge of condenser 22. On the decay of the pulse current, this energy, combined with that stored in the coil 21 and the slug 23, operate to maintain the magnetic flux in the core, in accordance with Lenz's law. The armature is thus held firmly to the core during the decay of the pulse and thereafter. The release time is controlled by the amount of charge on the condenser 22 and the time required for the current thru coil 21, due to this charge, to decay until the holding current in the coil 21 drops below minimum value. The variable resistor 19, located in the circuit as shown in Fig. 17, provides a convenient means for adjusting electrically the release time of the relay without the necessity of change in design, or mechanical adjustment of the relay. It is to be noted that the location of resistor 19 in the circuit is such as not to interfere with the operating pulse, but acts only to retard the discharge of condenser 22 thru the coil 21. Where such adjustment of the release time is not required, the resistor 22 may be omitted without detriment, provided the resistance required to produce the release time desired is incorporated in the coil 21.

It is to be noted that the role of the slug 23 is materially different in the present invention from that played in the types of slow release relays heretofore known. In such prior types,

the release time is mainly dependent on the energy induced in the slug (stored in the form of circulating current) by change in the magnetic flux in the core 15. In the present invention, the release time is controlled almost exclusively by the charge on the condenser 22 and the characteristics of the coil 21, any contribution from the slug being inconsequential. For certain values of capacity of the condenser 22 and of inductance and resistance of the coil 21, an oscillatory discharge of energy between the condenser 22 and coil 21 may occur. For other combinations, a reversal of flux may occur when the circuit including the windings of the release relay is broken. In such instances the relay may release the armature 16 momentarily, causing an unwanted drop out. The slug 23, by its damping action, opposes sudden magnetic changes, and causes the relay to hold without chatter or release during transient conditions in the circuit. The damping action of the slug 23 is of importance in cases where the relay tends to chatter or drop out momentarily. In cases where such tendencies do not exist, the slug 23 may be dispensed with.

The relay described is capable of quick operation when supplied with impulses of short duration; of holding firmly over periods of as much as a second after the energizing current has been cut off; and of being re-energized by short current pulses recurring periodically. It is further characterized by the principle of storing the energy for holding the relay in an operated condition in an associated condenser, which condenser is charged partly by the pulse current and partly by energy generated in the holding winding by transformer action from the operating winding. The characteristics and principle of operation of this relay are such as to constitute a generic class distinguished from prior forms of quick acting, slow release relays.

The motor governor

Referring to Figs. 18 to 21 inclusive, the motor governor 100, which is of the electrical type, consists of a disc 101 of insulating material, mounted on a hub 102, which in turn is mounted on the motor shaft 103 by set screw 104. On the periphery of the disc 101 are mounted two slip rings, 104 and 105, by which means current is led to the governor. The contact bracket 107 is held in place by two screws 110 which pass thru the disc 101 and terminate in slip ring 104 making electrical contact therewith. In the upturned portion of the bracket 107 is threaded the adjustable contact screw 111 having at the end 50 a contact 112.

The governor bracket 108 mounts the kinetic members, namely the tongue 113 and the governor spring 114. The tongue 113 is of special construction, consisting of a flexible strip 115, and a bi-metal strip 116 secured together by rivets 117, as shown (see Fig. 20). As is well known, bi-metal consists of sheets of two metals of dissimilar co-efficients of expansion, usually welded together to form one laminated sheet or strip. It has the property of exhibiting curvature when heated, the degree of such curvature being to a certain extent proportional to the change in temperature from the particular temperature at which the bi-metal is flat or straight. Metals commonly used in producing bi-metal are brass and steel, and brass and Monel metal.

At the outer end of the bi-metal strip 116 is mounted the movable contact 118, positioned to lie flat against the stationary contact 112 when 75

their surfaces are in contact. The tongue 113 is conveniently mounted on a support 120 by means of a screw 121 and clamp 122. The support 120 is part of the governor bracket 108. Near the 5 middle of the tongue is a hole into which is inserted the swivel pin 123, having a hole into which is threaded one looped end of the governor spring 114. The governor bracket 108 is mounted on the disc 101 by two screws 119 at 10 one end, which screws terminate in the slip ring 105 making electrical contact therewith. The contact bracket 107 and the governor bracket 108 are insulated electrically, except when the contacts 112 and 118 are closed. A portion of the 15 governor bracket 108 is upturned to form the support 126 upon which is mounted the flexible adjusting lever 125. The free end of the adjusting lever is turned inwardly and is perforated by a small hole into which is threaded a looped 20 end of the spring 114 as shown. Between the bent portion of the adjusting lever 125 and the support 126, the adjusting lever is pierced by a hole, thru which is assembled the micrometer adjusting screw 126, screwed into the support member 127.

The operation of the governor is as follows: Assume that the governor is rotating in a counter-clockwise direction as viewed in Fig. 18. At a 30 particular speed, the centrifugal force on the tongue 113 will exceed the spring tension in the spring 114, and the contacts 112-118 will open. When these contacts open, the resistance R2 is inserted in series with the motor as shown in Fig. 21. The motor is thereby slowed down, 35 causing the contacts to close, again speeding up the motor. This process is repeated many times a second, the motor not reaching a stable speed, but varying minutely above and below the speed at which the contacts open. This type of governor is well known, and it is to be observed that both the inertia of and centrifugal force on the tongue 113 contribute to the regulating action. It has therefore been called a centrifugal-inertia 40 governor. It is characterized by its sensitivity and accuracy of regulation.

The novel features of the present invention reside in the means for temperature compensation and for minor speed adjustment. It is evident that the tension in the spring 114 determines the speed to which the motor is regulated. An increase in the temperature of spring 114 results in a slight decrease in its tension, lowering slightly the regulated speed of the motor. This effect is compensated for in two ways. The 50 governor bracket 108 is held in position at one end by screws 119, the other end being free to move endwise only. The tensioning lever 125 and the adjusting screw 126 are mounted at the free end of the governor bracket 108. As the temperature of the governor increases, the governor bracket 108 is extended endwise by thermal expansion, stretching to a slight extent the spring 114, thereby increasing its tension and compensating in part for the decrease in tension due to 55 temperature. The compensation gained by this means is limited, however, by the thermal expansion of the material of the governor bracket along its length, and since the length of wire in the spring is much greater than the length of the 60 governor bracket, compensation over a considerable range of temperature is not readily accomplished by this means alone. The second temperature compensation means is provided by the 65 bi-metal strip 116 forming part of the tongue 113. As shown in Fig. 20, in exaggerated form,

when the temperature of the bi-metal strip 116 is increased, it curves convexly outward. Due to this curvature, the tension of spring 114 is increased with increase of temperature, compensating for its normal loss of tension with increase of temperature. By using proper bi-metal combinations and proportions of parts, determinable by well understood methods, thermal compensation of the governor may be accomplished over a considerable range of temperature. 10 With this improvement, the type of governor shown will regulate the speed of the motor with a high degree of precision under various conditions of temperature.

Minor speed adjustments

15

It would appear that the resistance R2, commonly called the gap resistance, if sufficiently large to slow the motor down to the speed set by the governor, would have little effect on the speed 20 set by the governor. Such is the case, but a minor change in speed does result from a comparatively large change in the value of the resistance R2. According to the present invention, this effect is utilized to accomplish minor adjustment of the 25 motor speed, without mechanical adjustment of the governor, the value of R2 being variable for that purpose.

It is to be noted that changing the value of the 30 gap resistance R2 is not equivalent to introducing a similar resistance into other parts of the motor circuit. Resistance placed in series with the motor, for example, has the same effect as a change of load, and is counteracted by the governor. The effect of such series resistance is also to impair 35 the range of regulation of the governor. A relatively large change in the gap resistance R2 does not limit to any material extent the range of regulation of the governor, but does produce a minor change in the speed set by the governor. 40

In printing telegraph systems, it is sometimes desirable to cause the sending instrument to run 45 slower by a constant amount than does the receiving instrument, or vice versa. In the present invention a change in the gap resistance is utilized to effect the desired constant speed difference. For this purpose, a resistance R1 is placed in 50 series with the variable gap resistance R2 but is normally short circuited by the contacts 109-109'. When these contacts are closed, the motor speed is regulated by the governor gap resistance R2 as previously described. When the contacts are open, additional resistance is introduced in the gap, and a minor but constant decrease in speed results. It is obvious that the same arrangement, 55 considering as normal the speed when contacts 109-109' are open, will produce a minor increase in speed when the contacts 109-109' are closed. The contacts 109-109 may consist of a switch, for local operation, or of the contacts of a relay for 60 remote control.

It is thus clear that the present invention provides a novel method of temperature compensation and minor speed control and adjustment for an electrical governor. The improved governor herein described is highly accurate, rapid and sensitive in action, self compensating for temperature changes, adapted to minor speed adjustments without stopping the governor or changing its mechanical adjustments, and particularly 70 adapted to control of incremental speed changes by remote control.

Spring link feature

As previously stated, the signal impulses and

operation impulses in a high speed printing telegraph are very brief in duration, and special provisions are necessary to assure certain response of relays and magnets to such brief impulses.

One of the features of the present invention is the means provided to assure efficient operation of the key solenoids and the key release solenoid. The solenoid possesses the advantages of simplicity and low cost, and of a long operating stroke. It is well known, however, that solenoids are inherently sluggish in response as compared to relays and magnets having short air gaps, and it has heretofore been the practice to use magnets adapted to quick response in the operation of printing telegraph mechanisms. The Hughes magnet employed in the Hughes printing telegraph is a well known example.

In the present invention, the plunger of each solenoid is connected to the member which it actuates by a resilient member consisting of a spring link 184 as shown in Fig. 23. The spring link is of the extension type with looped ends, one loop being threaded thru an eye in the reduced end of the plunger, the other loop being threaded thru a hole in the associated lever as shown. When the solenoid is energized the spring link is stretched and the plunger is quickly attracted, permitting the air gap to be closed, increasing the pull on the plunger. Were a resilient connection provided between the plunger and actuated member not provided, the entire mass of the plunger, connecting link, and actuated member would have to be accelerated in order to close the air gap. Since the effective mass of the actuated member is greater than that of the plunger and spring link, the action of the plunger would of necessity be slower, and less of the available magnetic energy could be utilized. As is well known, the pull on the plunger of a solenoid increases rapidly as the air gap is closed. The impact of the plunger is cushioned by the spring link and the pad 237, avoiding shocks to the mechanism.

The action of the spring link permits the key solenoid plunger to pull in without opening the key switch contacts, as explained under receiving operations, thus avoiding cutting off the energizing current before the completion of the current impulse.

Without further analysis, it will be perceived that manifold advantages are provided by the spring link feature.

Special space bar construction

All of the key levers of a typewriter, except the space key lever, are of substantially the same size and weight. The space bar normally extends across the greater part of the length of the key board, and is attached directly to the space key lever. While such construction is suitable for manual operation, for automatic operation by a magnet, the greater mass of the space bar and space lever would necessitate a more powerful magnet for operating this structure than is sufficient for the other key levers.

To overcome this difficulty, the special construction shown in Fig. 24 is used. The space key lever 220 is somewhat longer than the other keys, and has an extension 221, which extends beneath, but is not attached to, the space bar bail 222. Upon the bail 222 is pivotally mounted space bar 223. Not being attached to the space key lever 220, the space bar would normally tend to revolve about the bail 222, and would thus fall out of place. This tendency is corrected by the stem 224 which is attached to the space bar by screws

225 as shown, the lower end of stem 224 working in a slot 226 in bracket 227. A compression spring 228 is assembled on stem 224 between bracket 227 and washer 229, which bears against the shoulder 230 of stem 224. To prevent the spring 228 from moving space bar 223 above its normal level, the upward travel of stem 224 is limited by suitable means, such as the cotter pin 231, assembled in a hole thru stem 224 beneath bracket 227.

It will be apparent that by proper design, the spring 228 will support the weight of the space bar assembly without offering undue resistance to the touch of the operator. When operated manually the space bar is depressed as usual. When operated by the key magnet, however, the space bar remains in position, and only the space key lever 220 is pulled down. By means of this construction, normal manual operation of the space bar is provided, but for automatic operation, the power required is no greater than that required for the other keys, and the same quick and easy response is obtained without using a special larger key magnet.

Without further analysis, the foregoing will so fully reveal the gist of this invention that others can, by applying current knowledge, readily adapt it for various applications without omitting certain features which from the standpoint of prior art constitute essential characteristics of the generic or special aspects of this invention and therefor such adaptation should and is intended to be comprehended within the meaning or range of equivalency of the following claims.

I claim:

1. A system for synchronizing remotely situated periodic elements, which comprises instrumentalities for producing timed single impulses of definite periodicity, and means whereby said timed impulses are utilized to release the controlled element from a definite phase position thereby to establish synchronism with the periodic impulses, and corrector means actuated by the periodic impulses for correcting the phase position of the controlled element thereby to maintain synchronism.

2. A system for synchronizing remotely situated periodic elements which comprises instrumentalities for producing timed single impulses of definite periodicity, and means whereby said timed impulses are utilized to release the controlled element from a definite phase position thereby to establish synchronism with the periodic impulses, and corrector means including an electromagnet actuated by said timed impulses for correcting the phase position of the controlled element thereby to maintain synchronism.

3. A system for synchronizing remotely situated periodic elements, which comprises controlling instrumentalities for producing timed single impulses of definite periodicity, and means whereby said timed impulses are utilized to release the controlled element from a definite phase position, thereby to establish synchronism, and corrector means including a stationary electromagnet actuated by said timed impulses and a magnetizable member carried by the controlled member for correcting the phase position of the controlled member thereby to maintain synchronism.

4. A system for synchronizing remotely situated periodic elements which comprises instrumentalities for producing timed single impulses, and means including an electro-magnetically released clutch whereby said timed impulses are utilized to release the controlled element from

a definite phase position thereby to establish synchronism, and corrector means including a stationary electromagnet and a magnetizable member carried by the controlled member for 5 correcting the phase position of the controlled member thereby to maintain synchronism.

5. A system for synchronizing a periodic element with received periodic single impulses which comprises electromagnetically actuated release 10 means for establishing synchronism and corrector means including a stationary electromagnet and a magnetizable member carried by the controlled element for correcting the phase position of the controlled member, thereby to 15 maintain synchronism.

6. A system for synchronizing a controlled periodic element with received periodic single impulses which comprises release means actuated by said impulses to release the controlled element 20 from a definite phase position thereby to establish synchronism, and corrector means including a stationary electromagnet and a magnetizable member carried by the controlled member to maintain synchronism.

25 7. A system for synchronizing a controlled periodic element with received periodic single impulses which comprises electromagnetic release means actuated by said impulses to release said controlled element from a definite phase position, thereby to establish synchronism, and corrector means, including an electromagnet actuated by said impulses and a magnetizable member carried by the controlled element to correct the phase position of said magnetizable member 30 35 thereby to maintain synchronism.

8. In a synchronous system, means for receiving periodic single impulses, means for utilizing said received impulses to release a yielding driven controlled element from a predetermined 40 phase position thereby to establish synchronism with the received impulses, and corrector means including a magnetizable member carried by said controlled element to correct the phase position of said controlled member thereby to maintain 45 said controlled element in synchronism with the received impulses.

9. In a synchronous system, a continuously 50 correcting phase corrector means comprising a stationary electromagnet, a rotary synchronized member, and a single bar of magnetic material carried by the synchronized member upon which the electromagnet operates to maintain phase synchronism of said member.

10. In a synchronous system, a rotary member 55 and continuous phase correcting means for said member including a stationary electromagnet, and a single magnetic bar carried by said rotary member upon which the electromagnet operates to maintain phase synchronism of said member.

60 11. In a synchronous system, a segmented distributor, a rotary contactor member, a continuously correcting phase corrector means for said contactor member including a corrector magnet, means for adjusting the corrector magnet concentrically relative to the distributor, and a single magnet bar carried by said rotary contactor member upon which the corrector magnet operates to maintain phase synchronism of said rotary contactor member.

70 12. In a synchronous system a segmented distributor, a rotary contactor, a single magnetizable pole piece carried by said contactor, a motor for driving said contactor, friction driving means for said contactor, and a continuously correcting phase corrector means including an elec- 75

tromagnet which operates directly on said magnetizable pole piece to maintain phase synchronism of said contactor.

13. In a synchronous telegraph system, a correcting circuit comprising means for receiving periodic signal impulses a rotary distributor for distributing current impulses corresponding to said signal impulses comprising a segmented distributor and rotary contactor, a motor for driving said contactor, an instrumentality for controlling the speed of said motor, an electromagnetic corrector device having windings connected to a single segment of the distributor and receiving current impulses from the distributor and means responsive to the electromagnetic corrector device comprising a magnetic pole piece carried by the rotary contactor, thereby to correct the phase position of the rotary contactor and maintain phase synchronism of said rotary contactor with said current impulses. 20

14. In a synchronous telegraph system, a correcting circuit comprising means for receiving periodic signal impulses, a segmented distributor for receiving and distributing current impulses corresponding to said signal impulses, an electromagnetic corrector device having windings connected to a segment of the distributor and receiving current impulses from the distributor, rotary contactor means, and means associated with the contactor means and responsive to the electromagnetic corrector device comprising a magnetic pole piece carried by the contactor means, thereby to correct the phase position of the contactor means and maintain synchronism of said contactor means with said received periodic current impulses. 25 30 35

15. In a synchronous telegraph system, a synchronizing circuit comprising means for receiving periodic signal impulses, a rotary distributor for receiving and distributing current impulses corresponding to said signal impulses, rotary contactor means forming part of the rotary distributor, detaining means for holding said contactor means at rest in a definite phase position, release means responsive to said current impulses for actuating said detaining means, thereby to establish synchronism of said contactor means with said current impulses from the distributor, and means responsive to the electromagnetic corrector device comprising a magnetizable member associated with and carried by said rotary contactor means, thereby to correct the phase position of the rotary distributor and maintain synchronism. 40 45 50

16. In a synchronous telegraph system, a synchronizing circuit comprising means for receiving periodic signal impulses, a rotary distributor for receiving and distributing current impulses corresponding to said signal impulses, rotary contactor means forming part of the rotary distributor, detaining means for holding said contactor means at rest in a definite relation to a particular segment of the distributor, release means responsive to said current impulses for actuating said detaining means, thereby to establish synchronism of said contactor means with said current impulses; a correcting circuit comprising aforesaid means for receiving periodic signal impulses, and aforesaid rotary distributor for receiving and distributing current impulses corresponding to said signal impulses, and an electromagnetic corrector device having windings connected to a segment of the distributor, and means associated with the said contactor means and responsive to the corrector device, 55 60 65 70 75

thereby to correct the phase position of the contactor means, and maintain synchronism of said contactor means with said received periodic current impulses.

5 17. In a synchronous telegraph apparatus, in combination, a rotary distributor for receiving and distributing current impulses corresponding to received signal impulses comprising a rotary contactor and a stationary segmented distributor, and an electromagnetic phase corrector comprising a stationary electromagnet and a magnetizable bar carried by the rotary contactor member of the rotary distributor whereby the phase position of the said rotary contactor member is corrected to maintain synchronism.

10 18. In a synchronous system, the method of automatically establishing and maintaining synchronism which consists of the steps of sending single impulses of definite periodicity from the controlling station, receiving said periodic impulses at the controlled station, utilizing a rotary contactor to receive and distribute current impulses corresponding to said signal impulses, and utilizing said current impulses to release the rotary contactor from a definite phase position to establish synchronism, and thereafter utilizing said current impulses to correct the phase position of the rotary contactor to maintain said rotary contactor in time and phase synchronism 30 with said received periodic impulses.

15 19. An electromagnetic phase correcting device comprising a stationary electromagnet with salient poles, and a magnetizable bar armature carried by a rotary contactor whose phase is to be corrected, said stationary electromagnet and said armature cooperating at one position in the cycle of movement of said armature to maintain unison in the motion of the armature in respect to the pulse of magnetic flux in said poles.

20 20. A clutch mechanism comprising an electromagnet to actuate the mechanism, a resilient roll carried by the drive shaft, a resilient roll carried by the driven member, a stop member carried by the driven member, a cam with ser- rated edges engageable with said resilient rolls, a stop on the cam engageable by the stop member carried by the driven member, a pivotally mounted pawl member, a second stop on the cam engageable by the pawl member, an accelerating 50 spring lever capable of rotating the cam and a member mounted on the cam operatively related to the accelerating lever.

21. A quick acting, slow release electromagnetic relay arrangement comprising a relay with two windings connected in series aiding relation, one winding consisting of fewer turns than the other, and a condenser connected across the winding having the larger number of turns.

22. A quick acting, slow release electromagnetic relay arrangement comprising a relay with a winding of comparatively small number of turns and of comparatively low resistance mounted on the armature end of the relay core, a winding with a comparatively large number of turns and of comparatively high resistance mounted on the mid-section of the core, said windings being connected in series aiding relation, and an energy storing condenser connected across the terminals of the high resistance winding.

23. A relay in accordance with claim 22, with a copper slug located on the heel end of the relay core.

24. An electromagnetic relay arrangement comprising a stationary magnetizable structure, an

actuated member, two windings connected in series aiding relation, an energy storing condenser connected across one of said windings, and means for varying the electrical constants of the arrangement for timing the operation of said arrangement.

5 25. In an input governor of the centrifugal inertia type for motors, in combination, an adjustable contact, a movable contact, a flexible mounting for the movable contact, adjustable tensioning means for establishing a definite force of contact between the adjustable and movable contacts, and automatic compensating means for compensating for the effect of temperature on the tensioning means.

10 26. In an input governor of the centrifugal inertia type for motors, in combination, an adjustable contact, a mounting for the adjustable contact, a movable contact, a flexible mounting for the movable contact, a stationary mounting for the fixed end of the flexible mounting, tensioning means for establishing a definite contact pressure between the adjustable and movable contacts, and automatic compensating means for compensating for the effect of temperature on 20 said tensioning means, said compensating means comprising in part a thermally expansible mounting means for the flexible contact mounting, and in part a bi-metal strip adapted to increase the tension of the tensioning means with increase 25 of temperature.

25 27. In a speed control system for motors, in combination, a centrifugal governor regulating the power input of the motor to maintain constant speed of the motor, and electrical means for minor speed adjustment of the motor, comprising a variable gap resistor connected across the contacts of the governor.

30 28. In a speed control system for motors, in combination, a centrifugal governor regulating 40 the power input of the motor to maintain constant speed of the motor, electrical means for minor adjustment of the motor speed, including the contacts of the governor and a variable resistance, and electrical means for incremental 45 adjustment of the motor speed comprising a fixed resistor in series with the variable resistor, and switching means for switching the fixed resistance into or out of series connection with the variable resistor.

35 29. A synchronous communication system comprising a typewriter, switching means associated with said typewriter whereby specific circuits are closed when each key of said typewriter is depressed, means for transmitting periodic single synchronizing signals and aperiodic single printing signals, a transmission circuit, means for receiving the transmitted synchronizing and printing signals, an electrical energy source, means for distributing current impulses corresponding to said signals, release means for utilizing said current impulses corresponding to the synchronizing signals to establish synchronism, means for utilizing the current impulses corresponding to the synchronizing signals to maintain synchronism, a typewriter, actuating means for said typewriter, and selector means for utilizing the current impulses corresponding to the printing signals to energize selectively the typewriter actuating means.

40 30. In a synchronous telegraph system, a typewriter, switching means associated with said typewriter whereby specific circuits are closed when each key of said typewriter is depressed, collector means including a rotary distributor where-

- by current impulses are produced in aforesaid closed circuits, means for transmitting periodic single synchronizing and aperiodic single printing signals, a transmission circuit, receiver means for receiving the transmitted synchronizing and printing signals, an electrical energy source, means for distributing current impulses corresponding to the signals, release means for utilizing the current impulses corresponding to the 5 synchronizing signals to establish synchronism, corrector means for utilizing the current impulses corresponding to the synchronizing impulses to maintain synchronism, a second typewriter, actuating means for said typewriter and 10 selector means for utilizing the current impulses corresponding to the printing signals to energize selectively the typewriter actuating means.
31. In a synchronous communication system, instrumentalities for producing periodic and aperiodic single impulses, means for transmitting said 15 periodic and aperiodic impulses, a transmission circuit, receiver means for said periodic and aperiodic impulses, distributor means for distributing current impulses corresponding to said periodic and aperiodic impulses, release means utilizing said periodic current impulses to establish synchronism of said distributor means with the current impulses corresponding to said periodic impulses, corrector means utilizing said 20 periodic current impulses to maintain synchronism and multiple mechanism actuating and selector means utilizing said aperiodic current impulses to energize selectively said mechanism actuating means.
32. In a synchronous telegraph system, a printer mechanism, multiple actuating means for said printer mechanism, multiple switching means associated with said actuating means whereby a specific circuit is closed by each actuating means, a rotary contactor means successively closing each specific circuit, aperiodic impulse transmitting means, and non-repeat means whereby any specific circuit is effective to transmit a single impulse only for each operating cycle 25 of a particular actuating means.
33. In a printing telegraph system, a plurality of printer actuating levers, switching means associated with each actuating lever, switching means associated with the plurality of actuating levers, rotary distributor means, including a plurality of segments, each segment being connected to a particular switching means, and a non-repeat system comprising a relay, the switching means associated with the plurality of actuating 30 levers, and a circuit common to the particular switching means, whereby a single impulse is transmitted for each operating cycle of a particular actuating lever.
34. In a printing telegraph system, transmitting means comprising a plurality of printer actuating levers, individual switching means actuated by each actuating lever, latch means engaging the plurality of actuating levers and effective to retain any actuating lever in the 35 depressed position, an impulse transmitting circuit, an auxiliary circuit, relay means connected in the impulse transmitting circuit, and latch releasing means associated with the auxiliary circuit and controlled by said relay means whereby the latch is removed from engagement with the actuating levers when an impulse passes thru the impulse transmitting circuit.
35. In a printing telegraph transmitting system, a combined non-repeat and key release 40 system, including a plurality of key levers, lever latch means, individual switching means actuated by each key lever, switching means associated with the plurality of key levers, relay means, a circuit common to the said switching means and the relay means, an auxiliary circuit controlled by the relay means, and latch release means included in the auxiliary circuit and energized in response to current variations in the common circuit, the combination cooperating to prevent false repeat signals from being transmitted, and 45 to hold the key latch out of engagement until all key levers are released.
36. In printing telegraph key boards, in combination, a plurality of key levers, interlocking means whereby only one key lever at a time may 50 be depressed, key latch means operable to retain any key lever in the depressed position, and key latch release means responsive to the transmission of signal impulses to remove the key latch from engagement with the key levers.
37. In a printing telegraph system, a duplex calling circuit including a transmission line, an out-put transformer, an in-put transformer, with center tapped primary winding, a circuit from the transmission line including one winding of the 55 out-put transformer and connected to the center tap of the in-put transformer winding, a second circuit from the transmission line including a line compensating network and the primary of the in-put transformer, relay means, a secondary 60 circuit including the secondary of the in-put transformer and the energizing circuit of said relay, and an auxiliary circuit controlled by the relay and including a signalling device.
38. In a synchronous printing telegraph system, a circuit for transmitting periodic synchronizing signal impulses, including a source of electrical energy; a condenser connected across said source; a rotary distributor including a segmented ring, a common ring, and a rotary contactor; an impulse shaping network connected to one segment of said segmented ring; a transmission line; and a transformer with primary connected into said circuit and with secondary 65 connected to said transmission line.
39. In a synchronous printing telegraph system, a circuit for receiving and utilizing periodic synchronizing signals to establish synchronism, including a receiving circuit; a transformer having its primary connected to said receiving circuit; a secondary circuit including the secondary of said transformer and a relay actuating circuit; a local source of electrical energy; an auxiliary circuit energized by said local source and including circuit completing relay means and 70 means for terminating the current; a distributor including a segmented ring, a common ring and a rotary contactor; and electromagnetic release means for said contactor included in said auxiliary circuit.
40. In a synchronous printing telegraph system, a circuit for receiving and utilizing periodic synchronizing signals to maintain synchronism, including a receiving circuit; a transformer having its primary connected to said receiving circuit; a secondary circuit including the secondary of said transformer and a relay actuating circuit; a local source of electrical energy; an auxiliary circuit energized by said local source and including circuit completing relay means and means 75 for terminating the current thru said relay means; a rotary distributor including a rotary contactor; and electromagnetic corrector means operatively related to said rotary contactor and included in said auxiliary circuit to maintain syn-

chronism of said rotary contactor with the periodic synchronizing signals.

41. In a printing telegraph system, a circuit for transmitting aperiodic printing signals, including a source of electrical energy; a rotary distributor including a segmented ring, a common ring, and a rotary contactor; individual switching means associated with printer mechanism actuating levers and connected to individual segments of said segmented ring; a transformer with primary connected to said common ring and with secondary connected with the line; an auxiliary circuit including printer actuating lever release means; and relay means for controlling 10 said auxiliary circuit, the winding of said relay means being included in the transmitting circuit.

42. In a printing telegraph system, a circuit for receiving and utilizing aperiodic printing signals, including a receiving circuit; a transformer having its primary connected to said receiving circuit; a secondary circuit including the secondary of said transformer and a relay actuating circuit; a local source of electrical energy; an auxiliary circuit energized by said local source 20 and including circuit completing relay means and means for terminating the current thru said relay means; a rotary distributor including a rotary contactor, a segmented ring and a common ring; and individual printer mechanism actuating electromagnets, each connected to an individual segment of the segmented ring and connected in common to one terminal of the local power source.

43. In printing telegraph apparatus, in combination, a printer mechanism; printing signal transmitting means comprising a plurality of printer mechanism actuating levers; individual switching means actuated by each printer mechanism actuating lever; operating means interposed 30 between each actuating lever and its associated switching means; switching means operatively associated with the plurality of actuating levers; lever latch means operatively associated with the plurality of actuating levers; lever latch release 40 means; and relay means responsive to the transmission of printing signals for controlling said lever latch release means.

44. In printing telegraph apparatus, a combination for increasing the average speed of 50 working, which comprises at the transmitting station a printer mechanism including space mechanism; a rotary distributor with a segmented ring, a common ring, and a rotary contactor; switching means for transmitting signals to indicate the operation of the printer space 55 mechanism, said switching means being connected electrically to two segments of the segmented ring situated substantially diametrically opposite; and at the receiving station, receiving means; a rotary distributor with a segmented ring, a common ring, and a rotary contactor, a printer mechanism including space mechanism; and selective actuating means for the space mechanism of the printer mechanism, said actuating means being connected electrically to two segments of the segmented ring which correspond in position to the two space segments of the transmitting station; the combination reducing the average transmission interval of space 60 signals to substantially one half of the normal signal transmission interval.

45. In printing telegraph apparatus, in combination, printer control apparatus comprising: a rotary distributor, including a segmented commutator, a common ring, and a rotary contactor;

a driving motor for said rotary contactor; automatic release means for the rotary contactor whereby the rotary contactor is released from a predetermined position in response to a received synchronizing impulse to establish synchronism; phase correcting means for said rotary contactor; a local source of electrical energy; local circuit-completing relay means responsive to received signal impulses; and circuit-opening relay means to cut off local impulses initiated by said circuit-completing relay means thereby to eliminate 10 sparking at the distributor and to enable the printer mechanism to clear before a succeeding printer operation is initiated.

46. In printing telegraph apparatus, in combination, a printer key board having a plurality of key levers, and printer key board control apparatus for preventing the transmission of false signals comprising: individual signal transmitting means actuated by each key lever; switching 20 means operable by any one of the plurality of key levers; lever latch means capable of holding any one of said key levers in the operated position; electromagnetic actuating means for said lever latch means; relay means controlling said electromagnetic actuating means energized upon transmission of a signal and causing the lever latch means to unlatch; and switching means adapted to establish electrical conditions for the functioning of said control apparatus at the will 30 of the operator.

47. A clutch mechanism comprising a resilient member carried by the drive shaft, a resilient member carried by the driven member, a stop carried by the driven member, a cam member engageable with said resilient members; detent means on the cam member engageable by the stop of the driven member, resilient rotative means for said cam, detent means for said cam, and actuating means for said last named detent 40 means.

48. In communication apparatus, the combination of a gas content electronic relay tube having a cathode, a control grid, and an anode or plate and circuits therefor; a source of electrical energy for said circuits, a source of grid potential large enough to normally overcome the tendency of the gas in the tube to ionize, means for applying an operating potential to the grid, a rotary distributor, a device in the plate circuit responsive to the plate current, and relay means in the plate circuit functioning independently of said rotary distributor for opening the circuit thereof after a predetermined time interval.

49. In communication apparatus, the combination of a gas content electronic relay having a cathode, a control grid, and an anode or plate, and circuits therefor; a source of electrical energy for said circuits, a source of grid potential large enough to normally overcome the tendency of the gas in the tube to ionize, means for applying an operating potential to the grid, a rotary distributor, and relay means in the plate circuit functioning independently of said rotary distributor and responsive to the plate current during ionization for breaking the plate circuit after a predetermined time interval.

50. In communication apparatus, the combination of a gas content electronic relay tube 70 having a cathode, control grid and a plate, and circuits therefor; a source of energy therefor including a source of grid bias potential large enough to normally overcome the tendency of the gas in the tube to ionize, means for supply- 75

ing an operating potential to the grid, stabilizing means for the grid to prevent premature operation due to stray potentials, a device in the plate circuit responsive to the plate current during ionization, and relay means in the plate circuit responsive to the plate current during ionization, and effective after a controlled interval to break the plate circuit.

51. In communication apparatus, the combination in accordance with claim 50, and stabilizing means for the grid biasing potential to render same substantially uniform during momentary fluctuations in the electromotive force of the source of energy.

52. An electromagnetic relay arrangement comprising a stationary structure of magnetic material, an actuated member, two windings connected in series aiding relation, and an energy storing condenser connected across one of said windings.

53. A relay arrangement in accordance with claim 52; and an energy storing damping device mounted on said stationary structure.

54. In a printing telegraph system, a printer mechanism, multiple actuating means for said printer mechanism, a specific circuit arranged to be closed by each actuating means upon actuation thereof, rotary contactor means successively closing each said specific circuit, signal impulse transmitting means, and non-repeat means adapted to prevent the transmission of more than one effective signal impulse for each operating cycle of any actuating means.

55. In printing telegraph apparatus in combination, a printer mechanism, a printer keyboard having a plurality of key levers each controlling a particular operation of said printer mechanism, individual electromagnetic actuating means for each of said key levers, a local source of electrical energy, a rotary distributor adapted to connect successively each of said electromagnetic actuating means in circuit with said local source of energy, circuit completing relay means responsive to received signal impulses and adapted to complete the circuit including said local source of energy, said rotary distributor, and an individual electromagnetic actuating means; circuit opening relay means adapted to cut off after a predetermined interval local impulses initiated by said circuit completing relay means thereby to eliminate sparking at the distributor and to enable the printer mechanism to clear before a succeeding printer operation is initiated, and means associated with said relay means for predetermining said time interval.

56. In printing telegraph apparatus, a printer mechanism, means including a rotary distributor for selectively operating said printer mechanism, relay means adapted to cut off operating impulses after a predetermined time interval thereby to eliminate sparking at the rotary distributor and to prevent maloperation of said printer mechanism, and control means other than said rotary distributor in a circuit with said relay means for predetermining said time interval.

57. A system for synchronizing a controlled element with a moving controlling element which comprises means for driving said controlled element at a speed substantially the same as the speed of said controlling element, means for producing periodic impulses representative of a predetermined phase position of said controlling element, means responsive to said periodic impulses for releasing said controlled element from a predetermined phase position to establish substan-

tial synchronism with the periodic impulses, and means responsive to said periodic impulses for correcting the phase of said controlled element to perfect and maintain the synchronism of said controlled element with said controlling element. 5

58. A system for synchronizing a controlled element with a moving controlling element including means for producing and transmitting periodic impulses representative of a predetermined phase position of said controlling element, 10 receiving means for said periodic impulses, means for driving said controlled element at a speed substantially the same as the speed of said controlling element, means responsive to said periodic impulses for initiating the driving movement of said controlled element by said driving means from a predetermined phase position to establish substantial synchronism with said controlling element, and means responsive to said periodic impulses for correcting the phase of said 20 controlled element to perfect and maintain synchronism of said controlled element with said controlling element.

59. A system for synchronizing a rotary element with received periodic impulses including means for driving said rotary element in approximate timed relation with said impulses, electromagnetically actuated means for initiating the driving of said element by said driving means from a predetermined phase position to establish 30 substantial synchronism of said rotary element with said impulses, and electromagnetically actuated means for correcting the phase of said rotary element to perfect and maintain synchronism of said rotary element with said impulses.

60. A communication system of the character described comprising a first typewriter, switch means associated with said typewriter whereby specific circuits are closed when each key of said typewriter is actuated, means for producing periodic single synchronizing signals, means including said switching means for producing aperiodic single printing signals corresponding to the actuated typewriter key and distinguished in time with reference to said periodic synchronizing signals, means for receiving said signals, a second typewriter at the receiving station, actuating means for said second typewriter comprising circuits associated with each of the keys of said typewriter, means moving cyclically for controlling each of said circuits, means for driving said moving means in approximate timed relation to said received periodic signals, means for initiating driving movement of said driving means in response to said periodic signals to establish synchronism therewith, means acting in response to said periodic signals to maintain the synchronism of said moving means with said periodic signals, and means including said moving means for distributing impulses selectively to the circuits of said second typewriter in accordance with said aperiodic signals to effect selective operation of said second typewriter.

61. A communication system of the character described adapted for high speed operation comprising at the transmitting station, a printer mechanism including character mechanism and space mechanism, individual circuits associated with said character mechanisms, a plurality of circuits associated with said space mechanism, 70 means for periodically completing said character mechanism circuits in sequence and for completing said spaced mechanism circuits at spaced intervals in a cycle of operation of said means, means for transmitting signals corresponding to

the individual mechanism operated; and at the receiving station, a printer mechanism including character mechanisms and space mechanism, selective actuating means for said mechanism including circuits associated with said actuating means for the character mechanisms, and a plurality of circuits associated with said actuating means for the space mechanism, and means for receiving said transmitted signals and completing said circuits periodically in order corresponding to that at the transmitting station to cause selective operation of the printer mechanism at the receiving station.

62. In a communication system of the character described the combination of a key lever, electromagnetic key operating means, a circuit for energizing said operating means, circuit control means operated in response to actuation of said key lever for opening said circuit, a shut-off relay in circuit with said circuit control means and with said operating means for opening said circuit after a predetermined time interval, and means mechanically interconnecting said key op-

erating means and said key lever providing a delay in movement of the key lever in response to energization of said key operating means such as to delay the opening of said circuit control means until after the opening of said circuit by 5 said shut-off relay.

63. In typewriter control apparatus, means for actuating the space mechanism including a space key lever, a space bar adapted to actuate said space key lever under manual control and electromagnetic means adapted to actuate space key lever independently of said space bar.

64. In a communication system of the character described, for selective transmission and reception, a printer mechanism having a plurality 15 of character printing keys and a space mechanism, manually operable means for effecting actuation of said space mechanism, and means responsive to received signals for actuating said space mechanism independently of said manually operable means.

HARRY J. NICHOLS.
